UNITED STATES PATENT OFFICE.

GUSTAVE M. MINTON, JR., OF NEW YORK, N. Y.

DESIGN FOR A CAP FOR ATOMIZERS.

Application filed January 20, 1928. Serial No. 24,941. Term of patent 14 years.

To all whom it may concern:

Be it known that I, GUSTAVE M. MINTON, Jr., a citizen of the United States, residing at New York, in the county of New York and State of New York, have invented a new, original, and ornamental Design for Caps for Atomizers, of which the following is a specification, reference being had to the accompanying drawings, forming part thereof, and in which:—

Figure 1 is an elevation of the cap for atomizers.

Figure 2 is a perspective of same.

I claim:

The ornamental design for a cap for atomizers, as shown.
